(**) Term: **14 Years**

(57) **CLAIM**

(21) Appl. No.: **29/115,005**

The ornamental design for a line slider for a spinning fishing reel, as shown and described.

(22) Filed: **Dec. 7, 1999**

DESCRIPTION

(30) **Foreign Application Priority Data**

Jun. 8, 1999 (JP) 11-14965
Jun. 8, 1999 (JP) 11-14966

(51) **LOC (7) Cl.** **22-05**

FIG. 1 is a perspective view of the top, front and right side of a line slider for a spinning fishing reel showing our new design;

(52) **U.S. Cl.** **D22/143**

FIG. 2 is a front elevational view thereof;

(58) **Field of Search** D22/143, 142,
D22/141, 140, 137, 138; 43/9.8, 18.1, 19,
19.2, 20, 24

FIG. 3 is a right side elevational view thereof;

(56) **References Cited**

FIG. 4 is a top plan view thereof;

U.S. PATENT DOCUMENTS

FIG. 5 is a rear elevational view thereof;
